CAR HAUL

Carl Burkitt, Chicago, Ill., assignor to Link-Belt Company, a corporation of Illinois

Application March 27, 1953, Serial No. 344,947

12 Claims. (Cl. 104—172)

This invention relates to new and useful improvements in car haul mechanism for controlling the advance of trips of loosely coupled cars in either direction along an inclined track section, and deals more particularly with the downgrade advancement of such trips.

Car hauls of the aforementioned type have been used extensively at mines and other similar installations. In the past, however, it has been necessary to locate such hauls in level, or substantially level, portions of the track to ensure uniform spacing between the coupled cars while moving in either direction along the track to provide proper engagement between the cars and the pusher dogs of the haul. Where such a procedure is not practical, it has been necessary to install separate car hauls for moving the trips of cars upgrade and downgrade.

It is the primary object of this invention to provide a single car haul that is capable of engaging and moving trips of cars in either direction along an inclined track section.

A further important object of the invention is to provide a car haul which will effect the same spacing between the coupled cars of a trip regardless of whether the trip is moving downgrade or upgrade onto the haul with the result that the cars always will be properly engaged by the haul regardless of the direction of their movement.

Another important object of the invention is to provide a car haul with a device for maintaining the proper spacing between the coupled cars of a trip entering and moving with the haul on a downgrade so that the cars will be properly engaged by the pusher dogs of the haul to prevent over-running of the haul by the cars.

A still further important object of the invention is to provide a car haul which is capable of properly engaging the successive cars of a trip for moving the latter in either direction along an inclined track section due to the inclusion of a car retarding device at the higher end of the haul which will maintain the same spacing between the coupled cars moving with a haul in the downgrade direction as is automatically maintained by gravity for the cars moved by the haul in the upgrade direction.

Other objects and advantages of the invention will be apparent during the course of the following description.

In the accompanying drawings forming a part of this specification and in which like reference characters are employed to designate like parts throughout the same,

Figure 1 is a side elevational view of a car haul embodying the invention with a trip of cars in the positions they assume when the haul starts to operate,

Figure 2 is a similar view to Fig. 1 but showing the relative positions of the cars and the pusher dogs of the haul as the haul is further advanced,

Figure 3 is a similar view to Figs. 1 and 2 but showing the positions assumed by the cars and the pusher dogs after the retarding device has been released,

Figure 4 is a similar view to Figs. 1, 2 and 3 but showing the positions of the cars and pusher dogs just prior to the start of the haul,

2

Figure 5 is a longitudinal sectional view of the piston and cylinder portion of the retarding device,

Figure 6 is a fragmentary side elevational view of the retarding dog and its support,

Figure 7 is a vertical sectional view taken on line 7—7 of Fig. 6,

Figure 8 is a fragmentary side elevational view of one of the pusher dogs with its chain and supporting guideway, and

Figure 9 is a vertical sectional view taken on line 9—9 of Fig. 8.

In the drawings, wherein for the purpose of illustration is shown a preferred embodiment of this invention, and first particularly referring to Figs. 1 to 4, inclusive, in which there are illustrated four stages of downgrade advancement of a trip of cars A, B, C and D relative to a car haul, it will be seen that the cars A, B, C and D are supported by the rails 11 of a section of track. The rails 11 extend along a surface that is sloped or inclined in the direction indicated by the legends on Figs. 1 to 4, inclusive. Adjacent ends of the cars A, B, C and D are coupled together by any suitable means, such as the pins 12 which pass through the openings in the coupling links 13, see Figs. 2 and 3, and through the tongues 14. The openings in the coupling links 13 are elongated to permit limited movement of the pins 12 in the openings and corresponding movement of the coupled cars toward and away from each other.

Positioned between the rails 11 in a pit 15, or the like, is a car haul which includes an endless chain 16 that extends between terminal sprockets 17 with its active run supported by a guideway 18 in parallel relationship with and at the level of the track rails 11. One of the sprockets 17 is driven either intermittently or continuously by a reversible motor 19 which is drivingly connected to the sprocket by a belt 19a, or the like.

At uniformly spaced positions along the chain 16 are a suitable number of control devices that are each formed of a pair of attachment links 20 which are mounted in 40 and form pitches of the chain and a pair of pusher dogs 21 which are oppositely arranged and pivotally mounted on the attachment links. The pusher dogs 21 are so balanced as to be actuated by gravity for movement into their car engaging positions while passing through the active run of the chain. While in their car engaging positions, the pusher dogs 21 of each pair present opposed contact faces 22 that are normal to the direction of movement of the chain 16. The dogs 21 will not pivot as a result of the application of pressure to their faces 22 because the rear portions of the dogs engage their attachment links 20, as seen in Fig. 8. The pusher dogs 21, however, are free to pivot in the opposite direction. Control projections for cooperating with the control devices are provided by the depending lugs 23 which are similarly mounted on the cars A, B, C and D to present oppositely directed control faces for engagement with contact faces 22. The lugs 23 are free to move in either direction into the spaces between the opposed faces 22 of the pairs of pusher dogs but are prevented from moving out of such spaces until the chain 16 has passed around a terminal sprocket 17 a sufficient distance to withdraw the lugs from between the dogs.

Mounted between the rails 11 at the upper end of the car haul is a retarding mechanism that comprises a reciprocal control device and a counterweighted, one-way acting dashpot unit for governing the movements of the said control device.

The dashpot unit includes a cylinder 24 having its axis in parallel relationship with the rails 11. As is best illustrated in Fig. 5, the cylinder 24 has mounted for longitudinal movement therein a piston 25 having operating rods 26 and 27 extending in opposite directions there-

from. Positioned between the piston 25 and the outer end wall of the cylinder 24 is a stop collar 28. The inner end portion of the cylinder 24 is provided with two longitudinally spaced, side wall apertures 29 and 31 while a third aperture 32 extends through the side wall into the clearance space provided by the stop collar 28. The piston 25, therefore, is movable in opposite directions between a position abutting the stop collar 28 and a position adjacent the aperture 29.

The apertures 29 and 32 are connected to the opposite ends of a pair of parallel branch pipes 33 and 34. Mounted in the branch pipe 33 is an adjustable orifice valve 35 for controlling the rate of flow of fluid through this pipe. Branch pipe 34 is provided with a check valve 36 for permitting only unidirectional flow of fluid from the aperture 32 toward the apertures 29 and 31. The branch pipe 34 also is connected to the aperture 31 to thereby permit the free flow of fluid between the apertures 29 and 31.

Connected to the operating rod 26 by a cable 37 is a counterweight 38 which is suspended from the pulley 39 to urge the piston 25 toward its stop collar 28. Mounted in the outer end portion of the operating rod 27 is a turn buckle 40 by means of which the length of this operating rod may be adjusted.

The outer end of the rod 27 is pivotally connected to a control device, as illustrated in Figs. 6 and 7. The control device consists of a carriage 41 formed of a pair of transversely spaced side bars 41a that are connected by a pair of longitudinally spaced axes 42 upon which are mounted wheels or rollers 43 and a retarding dog 44 that is pivotally mounted between the side bars 41a. The retarding dog 44 is gravitationally actuated for movement to a normal position at which the dog is held against further pivotal movement in a backward direction by its engagement with one of the axes 42.

The carriage 41 is supported by a guideway formed of a pair of oppositely arranged, inwardly opening channel beams 45 mounted on brackets 46. The channels 45 extend in parallel relationship with the rails 11 to support the carriage 41 for movement with the cars A, B, C and D for a distance that corresponds with the travel of the piston 25 between its stop collar 28 and a position just beyond the aperture 31. The channels 45 thereafter are inclined downwardly in angular relationship with the rails 11 to effect pivotal movement of the carriage 41, relative to the rod 27, as the piston 25 is moved the remainder of its distance of travel through the cylinder 24. The retarding dog 44 thereby is caused to move downwardly a sufficient distance to clear the lugs 23 on the cars. It will be readily apparent that the lugs 23 of the cars moving in an upgrade direction will merely effect pivotal movement of the retarding dogs 24 and will have no effect on the position of the carriage 41.

Operation of the car haul in effecting movement of a trip of cars downgrade will be described as follows:

First referring to the disclosure provided by Fig. 4, it will be assumed that the car haul has been stopped with one of its pairs of pusher dogs 21 positioned in the upper run of the chain 16 at a location which is no further advanced to the right than is illustrated in this figure. When so arranged, the next succeeding pair of pusher dogs will be positioned below the path of movement of the car lugs 23.

In assuming this starting position, the first two cars of the trip have advanced by gravity down the rails 11 and their lugs 23 have successively engaged and actuated the retarding device. That is to say, the lugs 23 of the cars A and B have successively engaged the retarding dog 44 of the carriage 41 and have advanced the carriage a sufficient distance along its channel beams 45 to permit the lugs to clear the dog 44. The lug 23 of the car A is illustrated as engaging the contact face 22 of its leading dog 21. Because the car haul is not being driven by

the motor 19, this engagement of the lug 23 of car A will cause the haul to hold the entire trip of cars with their tongues 14 in abutting engagement. It will be noted that the lug 23 of car B is clear of both of its pusher dogs 21 while the lug 23 of car C is substantially spaced from the retarding dog 44.

Fig. 1 is intended to illustrate the relative positions of the various cooperating elements after the car haul has been placed in operation and the cars A, B and C have advanced to the illustrated positions. When thus arranged, the lug 23 of car A is still engaging the contact face of its associated, leading pusher dog 21, while the lug 23 of car B is overlying the leading pusher dog of its associated pair, and the lug 23 of car C has just engaged the retarding dog 44. Up to this point, the engagement of the lug 23 of car A with its associated leading pusher dog 21 has held the entire trip of cars from advancing at too rapid a rate down the rails 11.

Fig. 2 illustrates the relative positions of the various cooperating elements after the chain 16 of the car haul has advanced a sufficient distance to position the second pair of pusher dogs in its upper run. The retarding device has functioned, due to the engagement of its dog 44 with the lug 23 of car C, to restrain the forward movement of cars A, B and C sufficiently to cause the tongues 14 of these cars to be separated and the lug 23 of car A to engage the trailing pusher dog 21 of its associated pair while the lug 23 of car B is caused to enter the space between its associated pusher dogs 21. In other words, the car haul has been functioning to advance cars A, B and C against the retarding force exerted by the dog 44 and its associated mechanism. It, further, will be noted that the carriage 41 of the retarding mechanism has just started to move down the inclined portions of its supporting beams 45 with the result that further movement of the cars A, B and C by the haul will cause the lug 23 of car C to be moved out of engagement with the retarding dog 44.

Fig. 3 illustrates the positions assumed by cars A, B and C after lug 23, not shown, of car C has advanced beyond the retarding dog 44. It will be noted that cars A and B have coasted down the rails 11 a sufficient distance to cause the lug 23 of car B to contact the leading pusher dog 21 of its associated pair, while the lug 23 of car A has moved out of contact with the trailing pusher dog 21 of its associated pair. The leading pusher dog 21 associated with car B now is retarding all of the cars of the trip. Cars B, C and D will assume the positions occupied by cars A, B and C in the illustrations afforded by Figs. 1 and 2.

After the lug 23 of each car has advanced out of engagement with the retarding dog 44, the counterweight 38 will function to move the piston 25 from right to left through its cylinder 24 until the piston 25 again engages the stop collar 28. This movement of the piston 25 will cause the carriage 41 to be returned to the position illustrated in Fig. 1 where the retarding dog 44 will be in readiness to engage the lug 23 of car D.

The operation of the retarding mechanism to restrain the advance of each successive car of the trip will now be described.

The normal starting positions of the dog 44 and carriage 41 are illustrated in Figs. 1 and 4. The carriage is urged into this position by the action of the counterweight 38. When one of the car lugs 23 is moved into engagement with the dog 44, however, the dog and carriage will be moved along the guideway formed by the channels 45 in a direction away from the cylinder 24. This movement of the carriage 41 acting through the operating rod 27 will move the piston 25 away from its stop collar 28 and will force the fluid in the cylinder 24 at the right of the piston 25 to flow through the apertures 29 and 31, the branch pipe 33, the restricted orifice valve 35 and the aperture 32 into the opposite end of the cylinder at the

left of the piston 25. Due to the restriction provided by the valve 35, the rate of flow of the fluid is reduced sufficiently to cause the movement of the piston 25 to be retarded to the desired extent. It will be appreciated that the check valve 36 will prevent flow of fluid through the branch pipe 34 to the aperture 32.

When the piston 25 has been moved, by the force applied by the lug 23 to the retarding dog 44, to a position at which the aperture 31 is on the opposite side of the piston from the aperture 29, the carriage 41 also will have moved to the inclined portion of the guideway formed by the channels 45. At this time, the fluid flowing from the cylinder 24 through the aperture 29 is bypassed to the opposite side of the piston through the aperture 31 so that the retarding effect of the valve 35 is eliminated and the carriage 41 will move easily and quickly down the inclined portion of the channels 45 to release the retarding dog 44 from the lug 23, as illustrated in the broken-line position of Fig. 6.

After the retarding dog 44 is released from the lug 23, the carriage 41 will be quickly returned to its starting position by the counterweight 38 connected by the cable 37 to the operating rod 26. The movement of the piston to the left in its cylinder is unretarded due to the free flow of fluid through the aperture 32, the check valve 36 and the pipe 34 into the opposite end portion of the cylinder through both of the apertures 29 and 31.

Adjustment of the carriage 41 relative to the operating rod 27 by the turn buckle 40 will provide accurate spacing between the piston and the inclined portion of the channels 45 to provide the above described operation while adjustment of the orifice valve 35 will increase or decrease the retarding action of the dog 44.

It will be readily apparent that the retarding dog 44 will have no effect upon the cars of a trip that is moved up the inclined track and that such a trip will be stretched by gravitational pull to provide proper spacing between the lugs 23 of adjacent cars so that they will register with the pusher dogs 21.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In mechanism for controlling the advance down an inclined track section of a trip of cars loosely coupled together and each car having a control projection, an endless chain haul having its active run driven in the same direction as and in parallel relationship with the trip, a plurality of control devices attached to the chain haul at intervals which are spaced to operatively register with the control projections on adjacent cars of the trip when the cars are spaced the maximum distance permitted by their couplings, each of said control devices engaging its car control projection upon registering therewith to alternately restrain the coasting of the trip down the track section and apply a force to advance the trip down said track section, and a retarding mechanism positioned upgrade from the car haul for applying a retarding force to an adjacently positioned car of the trip each time a control device of the haul applies an advancing force to the trip to thereby space to the maximum distance the cars entering the haul so as to effect the registering of each car haul control device with the control projection of its respective car.

2. A mechanism as defined in claim 1 further characterized by said retarding mechanism having a reciprocating control device for successively engaging the control projections on the cars of the trip to apply said retarding force.

3. A mechanism as defined in claim 2 further characterized by the retarding mechanism including a one-way

acting dashpot unit for retarding the rate of movement of the reciprocating control device in one direction, and means for moving the said control device in the opposite direction at a more rapid rate.

4. A mechanism as defined in claim 2 further characterized by the reciprocating control device including a wheeled carriage, a dog pivoted on the carriage for engaging the control projections on the cars of the trip, and means for guiding the wheeled carriage during its reciprocating movements.

5. A mechanism as defined in claim 4 further characterized by a one-way acting dashpot unit for retarding the rate of movement of the wheeled carriage in one direction, and a counterweight for moving the carriage in the opposite direction.

6. A mechanism as defined in claim 4 further characterized by the guiding means for the wheeled carriage comprising a pair of parallel channel beams on which the wheels of the carriage travel, said channel beams having portions which extend in parallel relation with the track section on which the trip of cars travel and portions which are inclined downwardly in angular relationship to said track section.

7. A mechanism as defined in claim 6 further characterized by a one-way acting dashpot unit for retarding the rate of movement of the wheeled carriage in one direction, and a counterweight for moving the carriage in the opposite direction.

8. A mechanism as defined in claim 3 further characterized by the dashpot unit comprising a cylinder closed at both ends, a piston reciprocating in the cylinder, operating rods connected to the piston and extending through the opposite ends of the cylinder, means connecting one of said rods to the reciprocating control device, a counterweight connected to the other of said rods, means forming two parallel fluid flow paths between the opposite end portions of said cylinder, an adjustable orifice valve controlling the rate of flow of fluid through one of said flow paths to retard the rate of movement of the reciprocating control device in one direction, and a one-way acting check valve in the other of said flow paths permitting the free flow of fluid between the end portions of the cylinder in the direction to allow the counterweight to move the reciprocating control device in the opposite direction at a more rapid rate.

9. In a mechanism for controlling the advance down an inclined track section of a trip of cars loosely coupled together and each having a control lug, an endless chain haul having its active run driven in the same direction as and in parallel relationship with the trip, a plurality of pairs of dogs, having spaced contact faces, attached to the chain haul at intervals which are spaced to cause the contact faces to operatively register with the lugs of adjacent cars when the cars are spaced the maximum distance permitted by their couplings, said contact faces alternately engaging their associated lug to restrain coasting of and to advance the trip down the track section, and a retarding mechanism positioned upgrade from the car haul and having a dog mounted for retarded movement from its normal position by engagement with, and for subsequent release from, the lug of an adjacently positioned car, engagement between said retarding dog and a car lug causing a dog pair of the haul to advance said trip and effect said maximum spacing between cars entering the haul so that the lug of each car will register with the space between contact faces of its respective dog pair, and release of said retarding dog from a car lug permitting the trip to coast until restrained by said dog pair of the haul and permitting said retarding dog to return to its normal position.

10. A mechanism as defined in claim 9 further characterized by said retarding dog having a guideway with a major portion of its length in parallel relationship with said track to support the dog for movement by the lug and with its inner end portion inclined away from said

track to guide the dog into a position for release from said lug, and a fluid containing cylinder having a piston thereto connected to the dog for movement therewith against the pressure of the fluid in the cylinder to retard movement of the dog by the lug.

11. A mechanism as defined in claim 9 further characterized by a cylinder, a piston movable in said cylinder to inversely vary the volumes of the chambers on opposite sides of the piston, a pipe providing restricted communication between the chambers, a second pipe providing open communication between said chambers, a valve associated with said second pipe for preventing flow from one of the chambers to the other through the second pipe, and a rod extending from said piston for connection to the dog to cause movement of the latter by the lug to reduce the volume of said one chamber, said movement of the dog by the lug being retarded by the restricted flow of fluid from said one chamber to the other through the first mentioned pipe and return of the dog to its normal position being facilitated by free flow of fluid through said second pipe. 20

12. In mechanism for controlling the advance down an inclined track section of a trip of cars loosely coupled together and each having oppositely directed control faces, an endless chain haul having its active run driven in the same direction as and in parallel relationship with 25

said trip, a plurality of pairs of dogs, having spaced contact faces, attached to the chain haul at intervals which are spaced to cause the contact faces to operatively register with the control faces of adjacent cars when the 5 cars are spaced the maximum distance permitted by their couplings, said contact faces alternately engaging their registered control faces to restrain coasting of and to advance the trip down the track section, and a dog mounted for retarded movement from a normal position 10 upgrade from the haul toward said haul to a release position by engagement with a control face of an adjacently positioned car, retarded movement of said adjacently positioned car effecting the retarding of that portion of the trip upgrade from the retarding dog to cause a dog pair 15 of the haul to advance that portion of the trip downgrade from the retarding dog relatively to the remainder of the trip to hereby effect said maximum spacing between cars entering the trip.
